UNITED STATES PATENT OFFICE.

WALTER J. BEATTIE, OF COHOES, NEW YORK, ASSIGNOR TO THE BEATTIE MANUFACTURING CO., OF COHOES, NEW YORK, A CORPORATION OF NEW YORK.

MARKING MACHINE.

Application filed April 6, 1927. Serial No. 181,546.

The present invention relates to marking or stamping machines, and more particularly, to machines for stamping indicia upon sheet material.

5 In the manufacture of garments, for instance, it is customary after the garment is partially or wholly made up, to apply there-to minor parts, such as pockets, and it is necessary, in order that the garment may be considered perfect, that the pockets, or the like, be attached accurately and in proper position. If the pockets, for instance, are not in exact alignment, or arranged properly, the garment must be scrapped, or sold as 15 a "second".

An object of the invention is to provide a machine which will enable ready marking of the garment portion which receives attached parts, such as the pockets, in such 20 a way that the exact positions for the pockets and the like will be indicated to the garment maker.

Another object of the invention is to provide a machine for marking the portions of 25 the garments, which will receive the pockets or other parts, quickly and so that the time required for this operation will be substantially less than the time now required for determining, by measurement of the shirt front, the proper position for the pockets, thus considerably lessening the total time 30 required for manufacture.

In the accompanying drawings, a machine is shown which is constructed for the marking 35 of the pocket positions on shirt or blouse "fronts", although it will be understood that the invention is not limited to the marking of parts of this particular type, since without departure from the same, the invention may be readily applied to the marking of other types of garments, and the like.

Referring to the accompanying drawings, wherein there is shown this preferred embodiment:

45 Figure 1 is a top plan showing the outline of a shirt front positioned for marking.

Figure 2 is a front elevational view of the machine without material arranged thereon.

50 Figure 3 is a side elevational view showing a batch of material in position, with some of the pieces marked and folded from beneath the operative position of the marking elements to expose another blank of the batch.

Figure 4 is a perspective of a portion of the operating mechanism, looking from the rear.

Figure 5 is a horizontal section on the line 5-5 of Figure 3.

Figure 6 is a bottom plan of the operating mechanism beneath the material bed.

Figure 7 is a view of a portion of a shirt front with the pocket positions marked thereon.

Figure 8 is a top plan view of one of the marking elements with the plunger stem shown in section.

Figure 9 is a vertical section on the line 9-9 of Figure 8.

Figure 10 is a vertical section on the line 10-10 of Figure 8.

Figure 11 is a top plan view of a marking pad before it is applied to its carrier.

Figure 12 is a bottom plan of a marking element.

Figure 13 is a sectional view taken through the material clamping and gauge elements on the line 13-13 of Figure 1.

Figure 14 is a sectional view similar to Figure 13, taken on the line 14-14 of Figure 1.

Figure 15 is a horizontal sectional view on the line 15-15 of Figure 3.

Figure 16 is a detail view showing the support for the inking roller.

Figure 17 is a sectional view through one of the carrier arms on the line 17-17 of Figure 3.

Figure 18 is a horizontal sectional view through the slide bearing for one of the marking element plungers taken on the line 18-18 of Figure 3.

Referring to the drawings for a more detailed description, 10, 11, indicate a pair of supports having extending therebetween, a 95 carrier plate 12 for an operating mechanism, which will be later described, the plate being connected at its ends to strips 14 upon the supports, each strip having an upwardly extending sleeve 15. Upon the strips 14 is mounted a bed 16 having a front section 16' hinged thereto as by hinges 17, and adapted to be supported in the same horizontal plane with the bed (Figure 3) by means of jointed brackets 18.

The bed 16 is of sufficient size to receive a batch of material blanks B, which, in the present instance, are shown as shirt or

blouse "fronts", having the cut-away arm or sleeve portions S, the neck cut N and the front slit O (Figure 7) leading from the neck opening.

5 The "fronts", which are simply illustrative of any portion of a garment or the like, which is to be marked, are arranged upon the bed in packs or batches of superposed sheets or pieces, as illustrated in Figure 3, 10 and for the purpose of arranging the same in proper position, the bed has an upstanding gauge fin or web 19, which may be formed from any suitable material, such as sheet metal, and provided with laterally 15 projecting base lugs 20, through which screws 21 are passed to secure the same rigidly in position. This fin corresponds in size to the usual neck opening or slit O, and when the blank is arranged upon the 20 bed as illustrated in Figure 1, with the fin 19 projecting upwardly through the registering slits in the several pieces of the batch, the blanks are then in proper position.

For assisting in positioning the blanks 25 properly, an additional gauge means may be provided in the form of a transversely extending bar 22, having forked ends 23, adapted to straddle upwardly extending threaded pins 24, and to be clamped upon the 30 material by means of wing nuts 25 upon the pins. By means of the clamping bar 22 and wing nuts, the batch of material may be clamped in position after first being properly positioned with reference to the gauge fin 35 or web 19; and also with reference to a pair of plates 27 which are provided with grooves 28 (Figure 3) on their under surface to receive bar 22 and thereby enable the operator to arrange the plates at an absolute right 40 angle to the bar. These plates are of such length that their ends 27' are on a line with the rearmost edges of the marking elements when the latter is in operative position; hence, by determining the position of the 45 blank with respect to the ends of the gauge plates 27, the proper position of the latter for the marking operation may be determined. The plates are freely movable from their working positions shown in Figure 1, 50 and in order that they may be retained conveniently accessible or use in connection with the positioning of each new batch on the bed, are provided with securing ropes 29 connected thereto, and also to eyes 30 on the 55 supports for the machine, whereby they may be moved to their suspended position illustrated in Figure 3 when a batch of material has been properly positioned on the machine in the manner illustrated in Figure 1, and is 60 ready for the marking operation.

65 The marking mechanism comprises a pair of horizontally movable arms 31 at opposite sides of the batch of blanks, the arms being secured to vertical shafts 33 extending through the sleeves 15. The arms have at

their inner ends eyes 34 through which the shaft 33 extends, set screws 35 being employed to fasten the arms to the shafts.

Beneath the arm upon each shaft 33 is fastened a stop collar 36 having a depending lug 37 adapted to cooperate with the shoulders 38 at the upper end of the sleeve 15, which is cut away for a distance of 180 degrees to provide the stop shoulders, thus permitting the carrying arms to be swung, by mechanism later to be described, from the full line inoperative position of Fig. 1, in which they are arranged at the sides of the material, to the dotted line operative position in which they extend over the material. The outer ends of the arms have vertically disposed eyes 39, in which are vertically slideable plungers 40 retained in the eyes, which have open sides, by means of plates 41 (Figure 18) fastened to the arms by screws 42. The plungers and eyes are of angular formation in cross section, whereby the plungers are held against turning movement, and are simply permitted to slide vertically in the eyes 39.

90 Each plunger carries at its lower end a collar 43, which is secured thereto, as by a set screw 44, the latter serving also as an anchoring means for a flexible element 45, extending upwardly over pulleys 46, 47, and 95 carrying a counter-weight 48, which works vertically in a guide eye 49 upon the adjacent support for the bed. This counter-weight serves to maintain the plunger in raised position with the collar 43 abutting the lower 100 end of the plunger bearing eye 39, upon the carrying arm (Figure 3).

99 Each plunger carries at its lower end a marking element which is adapted to be forced upon the material when the arms are 105 swung to their operative position over the material by manually engaging the heads 40' of the plungers, and pressing the same downwardly. It will be understood, of course, that the character of the marking elements 110 will depend upon the formation of the part the position of which is to be marked. In the present instance, each marking element consists of the outline of a pocket, as shown in Figure 12, and has a rib R projecting 115 from a base R'. This marking element may be secured to each plunger in any suitable manner, and the particular form of attachment is shown in Figures 9 and 10. The web R' is secured by adhesion to a plate 49, and this has secured to its back, a metallic strip 50, having undercut lateral edges, which fit within a groove 51, having under-cut side walls (Figure 10), and arranged in the bottom of the collar 43. By this arrangement, the backing plate 49 and its marking element 120 may be adjusted upon the lower end of the plunger toward and from the axis of each arm, or, in other words, toward and from the shaft 33, whereby the spacing of the mark- 125 130

ing elements from one another and from the lateral edges of the material when in operative position over the latter, may be varied. That is to say, the sliding adjustment of the 5 marking elements enables the marking elements to be adjusted transversely of the blank relative to one another to conform to the varying spacing of pockets on "fronts" for shirts.

10 The marking elements and their carrying or backing plates, are held in position against accidental movement by means of a clamping screw 52, having a head 53, beneath the plate 51, and extending upwardly through the lat- 15 ter and the collar, an adjusting nut 54 on the bolt serving to clamp the backing plate 49 for the marking element, in any position to which it is adjusted.

Any suitable form of mechanism may be 20 employed for moving the carrying arms to and from their operative positions shown in dotted lines in Figure 1; in the mechanism illustrated each of the shafts 33 in sleeves 15, carries a pinion 55 (Figure 3) 25 with which mesh rack bars 56, slideable beneath plate 12 in the brackets 57 having lug portions 57' extending beneath the bars. The rack bars are actuatable in opposite directions by means of links 60, 61, connected 30 with short arms 62, projecting laterally from the rack bars, and at their other ends, with levers 63 upon short shafts 64 mounted in the lower ends of arms 65 of a forked bracket 65'. The link 61 is adjustably connected 35 with its lug 62 by means of nuts 66, mounted upon its threaded end whereby the connection with the associated carrying arm may be modified to vary the distance it swings; this adjustment of one arm may be 40 desirable at times to maintain the proper relation between the final operative positions of the arms at the end of the outward strokes of the two rack bars.

The bracket arms 65, extending down- 45 wardly from a top plate 67, toward which they converge upwardly, and the plate 67, is secured by means of bolts 68 to the mechanism carrying plate 12. The shafts 64 are rocked by means of levers 69 thereon ex- 50 tends inwardly and connected by links 70 to a block 71, secured to a pitman 72, which extends through an intermediate guide plate 73. The guide plate limits downward move- 55 ment of the pitman by engagement with block 71 and is rigidly held in position by means of rods 74, depending from plate 12, and carrying clamping nuts 75 on opposite sides of the guide plate 73.

At its upper end, the pitman 72 projects 60 into a guide sleeve 76, formed integrally with and depending from the plate 67 of the bracket 65', and at its lower end, it is connected with a cross rod 77 connecting the two treadle lever arms 78 which are ful- 65 crumed upon a cross rod 79. The levers

79 have forwardly extending arms 80 (Figure 3) at the front of the machine, which support a treadle 81.

As will be understood, when the treadle is depressed, the pitman 72 is forced upwardly and through the lever 69, rock shaft 64, and levers 63, actuates the rack bars and vertical shafts 33 to swing the marker carrying arms from the inoperative position shown in full lines to their dotted line po- 75

79 position in Figure 1. While the treadle is maintained depressed, the arms and marking elements will be held above the material on the bed, and the operator may manually force down the 80 plungers 40 to bring the marking elements into contact with the material immediately therebeneath. When the pressure upon the plungers is released, the counter-weights 48 will automatically draw them upwardly and 85 thus move the marking elements out of contact with the material. Release of pressure upon the treadle will permit the springs 87, connected to upwardly extending lever arms 88 and to a cross bar 89 upon 90 the supports (Figure 5) so that they will be tensioned by depression of the treadle, automatically to lower the pitman 72 and return the arms to inoperative position.

The arms are limited in their movement 95 to operative position by means of depending lugs 37 on stop collars 36, and by engagement of the upper end of the pitman with the top closed end of the sleeve 76 in which the upper end of the pitman works. Their movement to inoperative position by springs 87 is limited by the stop collars 36 and by engagement of pitman block 71 with the 100 guide and stop plate 73, the latter being vertically adjustable on threaded rods 74 105 through adjustment of clamp nuts 75 whereby it may be set to engage block 71 just as the stop collars 36 engage the shoulders on sleeves 15.

In order to provide for inking of the 110 marking elements, inking rollers 90 may have trunnions 91 supported in open substantially U-shaped bearings in the ends of an ink container trough 92, and one trun- 115 nion of each roller may be provided with a star wheel 93, arranged in the path of a pivoted trip 94, upon the carrying arms, so that as the arms move over the inking roller to operative position, the roller will be operated by engagement of the trip 94 120 with the star wheel; during return of the arms, the trip will freely swing in its pivot bracket 95 to permit the arm to pass the inking roller. The roller and ink container in which it is mounted, may be supported 125 by a depending pin 96 upon a saddle 97, which carries the container, and the lower end of the pin 96 rests upon a bearing screw 98, threaded in a substantially U-shaped bracket 99. Adjustment of the screw 98, 130

which serves as a support for the pin 96, will vary the height of the inking roller, which is desirable in order that the latter may be maintained at proper height to be wiped by the marking element as the latter passes over the same in moving from operative to inoperative position, and vice versa. The inking roller 90 rotates in engagement with an ink supplying roller 90', rotatable therebeneath within the container, and the supply roller, by contacting with the inking roller 90, maintains the surface of the latter sufficiently moist to supply the desired amount of ink to the marking element as it wipes the surface of the inking roller.

As has been explained, the movement of the inking roller is caused by the engaging of the marking element therewith, and it is also positively moved by engagement of the trip 34 with the star wheel 93, when the marking elements move from their inoperative to their operative positions.

The operation of the device will be substantially clear from the foregoing description. When a batch of blanks, such as the "fronts" of shirts or blouses, are to have the pocket positions marked thereon, they will be placed upon the bed, as illustrated in Figures 1 and 3. The clamping bar 12 will be positioned thereon, and before the clamping screws 25 are tightened, the garment pieces will be properly adjusted with relation to the gauge means, which comprises the web 19 projecting upwardly through the neck slits O, and the side gauge plates 27, which are constructed so that their ends 27' are on a line with the lateral edges of the marking elements when the latter are in the operative dotted-line position of Figure 1. In the marking of shirt fronts, it will be found desirable to have the lower edge of the sleeve openings S coincide with the ends of the gauge plates 27, as shown in Figure 1, since it is customary to place the pockets so that their upper open ends are on a line with the bottoms of the sleeve openings. By means of the plates 27, therefore, the position of the material blank with reference to the front edge of the bed plate may be readily determined, and the upwardly extending gauge web 19 determines the position of the material with respect to the sides of the bed, since, as will be understood, this web must project upwardly through the slits O in the material.

When the batch has been properly arranged in this manner, the gauge plates 27 are moved to the sides of the machine, where they are suspended by the tying elements 29, and the clamping bar 22 is secured in position by the tightening of the nuts 25. Pressure upon the treadle will swing the marker carrying arms 31 inwardly to their dotted line positions, and as long as pres-

sure on the treadle is maintained, the marker elements will be held in their operative position over the material. While holding the markers in this position by maintaining the treadle depressed, the operator may press down the plungers 40 carrying the marker elements, and thus mark the pocket positions on the top exposed blank. The result of this operation is shown clearly upon the marked blank illustrated in Figure 7. The counter-weights 48, automatically raise the plungers and marking elements, when the top exposed blank has been marked, and either while they are being raised, or immediately following the raising of the marking elements, pressure upon the treadle may be released which will permit the springs 87 to raise the treadle, and through the operating connections described, to swing the arms from their operative position over the material to their inoperative position at the sides of the material, as illustrated in Figure 1.

The marking elements will be inked by engagement of the same with the inking roller 91 during their movement to operative and inoperative positions, and fresh surfaces of the inking roller will be automatically presented to the marking elements during their successive movements to and from their extreme positions by actuation of the inking rollers through engagement of the trips 94 with the star wheels 93.

After each marking element has been moved to its inoperative position, the marked "front" may be folded over the clamping bar 22, as illustrated in Figure 3, to expose for marking the top surface of the under piece of material. It will be understood that after the pressure has moved the marked piece out of position, the treadle will be again depressed to move the marker carrying arms to operative position. These operations are repeated so long as there are blanks in the batch to be marked.

Obviously, the invention is not limited to the details of construction described, and such modifications may be made therein as come within the scope of the following claims.

What I claim as new and desire to secure by Letters Patent is—

1. A machine of the class described comprising a support for material to be marked, marking elements, a plurality of marking element supports movable to carry the marking elements to and from operative position in the same vertical plane with the material and a common means for actuating said supports.

2. A machine of the class described comprising a support for material to be marked, marking elements, a plurality of marking element supports movable horizontally to carry the marking elements to and from operative position in the same vertical plane

with the material and a common means for actuating said supports.

3. A machine of the class described comprising a support for material to be marked, marking elements, a plurality of marking element supports movable to carry the marking elements to and from operative position in the same vertical plane with the material and over it and a common means for actuating said supports.

4. A machine of the class described comprising a support for material to be marked, a marking element, a marking element support movable horizontally to carry the marking element to and from operative position in the same vertical plane with the material and pedal actuatable means for operating said support, said marking element being vertically movable manually upon its support and independently thereof to bring the element into engagement with the material.

5. A machine of the class described comprising a support for material to be marked, marking elements, a plurality of marking element supports movable horizontally to carry the marking elements to and from operative position in the same vertical plane with the material, and a common means for actuating said supports, said marking elements being vertically movable manually on their supports and independently thereof to bring the elements into engagement with the material.

6. A machine of the class described comprising a support for material to be marked, marking elements, a plurality of marking element supports movable to carry the marking elements to and from operative position in the same vertical plane with the material and over it, and a common means for actuating said supports, said marking elements being vertically movable manually on said supports and independently thereof to bring the elements into engagement with the material.

45 7. A machine of the class described comprising a support for a batch of pieces to be marked, gauge means on said support for the material, marking elements, a plurality of horizontally movable arms serving as supports for said elements, said arms being movable about vertical axes to carry said marking elements to and from operative position over the material, a common means for operating said arms, said marking elements being vertically movable toward and from the support.

8. A machine of the class described comprising a support for a batch of pieces to be marked, gauge means on said support for the material, marking elements, a plurality of horizontally movable arms serving as supports for said elements, said arms being movable to carry said marking elements to and from operative position over the material, and a common means for actuating said arms

with their respective marking elements, said marking elements being vertically movable on said arms and independently thereof into and out of contact with the material.

9. A machine of the class described comprising a support for a batch of pieces to be marked, gauge means on said support for the material, marking elements, a plurality of horizontally movable arms serving as supports for said elements, said arms being movable to carry said marking elements to and from operative position over the material, means for operating said arms, said marking elements being vertically movable on said arms and independently thereof into and out of contact with the material; said arms and marking elements, one being hand operable and the other foot operable.

10. A machine of the class described comprising a support for a batch of pieces to be marked, gauge means on said support for the material, marking elements, a plurality of horizontally movable arms serving as supports for said elements, said arms being movable to carry said marking elements to and from operative position over the material, means for shifting said arms and marking elements, said marking elements being vertically movable on said arms and independently thereof into and out of contact with the material, and means for automatically inking said marking elements as the arms carry the marking elements to and from operative position.

11. A machine of the class described comprising a support for a batch of pieces to be marked, gauge means on said support for the material, a marking element, a horizontally movable arm serving as a support for said element, said arm being movable horizontally to carry said marking element to and from operative position over the material, means for shifting said arm and marking element, said element being vertically movable on said arm and independently thereof into and out of contact with the material, and counter weight means associated with said marking element, serving to maintain the same normally raised above the horizontal plane of the material.

12. A machine of the class described comprising a support for a batch of pieces to be marked, gauge means on said support for the material including an upstanding member adapted to pass through a slit in the material, a marking element, a horizontally movable arm serving as a support for said element, said arm being movable to carry said marking element to and from operative position over the material, and means for shifting said arm and marking element.

13. A machine of the class described comprising a support for a batch of pieces to be marked, gauge means on said support for the material including an upstanding mem-

ber adapted to pass through a slit in the material, marking elements, a plurality of horizontal movable arms serving as supports for said elements, said arms being movable to carry said marking elements to and from operative position over the material, and means for shifting said arms and marking elements, said upstanding member being disposed between the marking elements when they are carried to operative position.

14. A machine of the class described comprising a support for a batch of flexible sheet material to be marked, gauge means on said support, a bar element adapted to extend over the material, an end of each sheet being individually foldable over said bar as the sheets are successively marked, a marking element, a supporting member for said elements movable toward and from the material to carry the marking elements to and from operative position over the material whereby the material may be conveniently folded over said bar.

15. A machine of the class described comprising a support for a batch of flexible material to be marked, gauge means on said support including an upstanding sheet-like member adapted to project through a slit in the material, a bar element adapted to extend over the material, an end of each sheet being individually foldable over said bar as the sheets are successively marked, marking elements, supporting members for said elements movable toward and from the material to carry the marking elements to operative position over the material and from said position whereby the material may be conveniently folded over said bar.

16. A machine of the class described comprising a support for a batch of flexible sheet material to be marked, gauge means on said support including an upstanding sheet-like member adapted to project through a slit in the material, a bar element adapted to extend over the material, an end of each sheet being individually foldable over said bar as the sheets are successively marked, marking elements, sup-

porting members for said elements movable toward and from the material to carry the marking elements to operative position over the material and from said position whereby the material may be conveniently folded over said bar, said upstanding member of the gauge means being arranged between the marking elements when they are disposed over the material in operative position.

17. A machine of the class described comprising a support for a batch of pieces to be marked, gauge means on said support for the material marking elements, a plurality of horizontally movable arms serving as supports for said elements, said arms being movable about vertical axes to carry said marking elements to and from operative position over the material, and means for shifting said arms and marking elements including vertically disposed rock shafts substantially coincident with the axes of said arms and carrying the arms, oppositely and horizontally movable members beneath said support and operatively associated with said shafts to rock the same, and pedal operable means for actuating said oppositely movable members.

18. A machine of the class described comprising a support for a batch of pieces to be marked, gauge means on said support for the material, marking elements, a plurality of horizontally movable arms serving as supports for said elements, said arms being movable about vertical axes to carry said marking elements to and from operative position over the material, and means for shifting said arms and marking elements including vertically disposed rock shafts substantially coincident with the axes of said arms and carrying the arms, oppositely movable rock bars beneath said support and operatively associated with said shafts to rock the same and pedal operable means for actuating said bars.

In testimony whereof I have hereunto set my hand.

WALTER J. BEATTIE.
